UNITED STATES PATENT OFFICE.

BESSIE ROBERTA CALLOW, OF SALT LAKE CITY, UTAH.

COIN-ENVELOP.

1,259,209.

Specification of Letters Patent. Patented Mar. 12, 1918.

Application filed March 15, 1917. Serial No. 155,054.

To all whom it may concern:

Be it known that I, BESSIE ROBERTA CALLOW, a citizen of the United States, residing at Salt Lake City, in the county of Salt Lake and State of Utah, have invented certain new and useful Improvements in Coin-Envelops, of which the following is a specification.

My invention relates to certain new and useful improvements in what are known as coin token or coupon envelops; that is, envelops, wrappers or other holders which are fashioned to provide pockets, or rows of pockets, each adapted to receive and retain, say, coins of the same or of different denominations, said envelops, wrappers or holders being provided with flap-portions which may be folded along one or more lines and the outermost part thereof secured in any suitable manner to afford safety for the contained coins in transmitting the envelops, wrappers or holders through the mails, or otherwise.

The leading object of the present invention is to provide an envelop, wrapper or holder of the character described, with a series of rows of pockets, each of said pockets being adapted to retain a coin, token or coupon, the coins, tokens or coupons of the same row being arranged in overlapping order, and the said envelop or holder having a flap-portion of sufficient size to entirely cover the several rows of pockets and the contained coins, tokens or coupons, and said flap-portion having an extension which may be folded over the outer side of the envelop to secure the contents, said extension serving, also, as a medium by which the envelop may be suspended to expose the entire series of pockets and the coins, tokens or coupons contained therein.

With the above and other objects in view, my invention consists of the improved coin, token or coupon envelop or holder which I will hereinafter describe and claim.

In the accompanying drawing forming part of this specification and in which similar reference characters indicate like parts in the several views;

Figure 1 is a front elevation of the envelop or holder in its open position.

Fig. 2 is an enlarged sectional view of the same on the line 2-2 of Fig. 1.

Fig. 3 is a sectional view of the envelop in its folded form.

Fig. 4 is a modification hereinafter referred to.

Fig. 5 is a fragment of one side of the envelop or holder showing a supplemental side flap.

In carrying out my invention I employ a sheet or blank of paper or other suitable flexible material, a substantial portion of which is folded upon itself to form plaits, A, which overlap and whose folds form the bottom of pockets, B, for the proper retention of coins, tokens or coupons placed therein. The folded or plaited portion of the paper or envelop and the folds or plaits of which may extend wholly or partially across the entire width of the sheet, I prefer to sub-divide into a series of rows of pockets. This may be done by lines of stitching, C, or by employing other means for fastening the plaits together at certain points to form the independent rows of pockets, before mentioned. When the sheet has been folded or plaited in the manner described, or in any substantially similar manner, and then sub-divided by the stitching, or other fastening means, to form the parallel rows of pockets, each of which will be found to be composed of individual pockets, the bottom of each of which is formed by the fold in the paper or sheet. The depth of the pocket will depend upon the width of the fold or plait; in practice it may be desirable that the depth of the pocket shall be equal to a portion only of the diameter of the coin to be inserted, when a coin is used, as in this case a substantial portion of the coin will be exposed above the open end of a pocket and will extend across in front of the next higher pocket and the inserted coins will be thus arranged in overlapping order so that when the several pockets of the envelop have been filled with the individual pieces and the envelop is folded along a line which is approximately a short distance above the entrance to the topmost

pockets, the several overlapping pieces of the rows will lie in substantially a common plane so that when the envelop is folded the exterior of the same will be devoid of substantial projections or irregularities; and the pieces will be slightly substantially wedged in place in their respective pockets to thus retain them in proper place during the transmission of the envelop through the mails, or otherwise. Above the folded or

plaited portion of the sheet, is a narrow unplaited portion, *a*, and above this (detachable if desired) a sheet, *C*, is provided with a flap-portion *c*, of a width substantially 5 equal to the width of the plaited portion of the paper and adapted to fold over the same, and if desired, the side edges of the sheet, *C*, may be formed with supplemental flaps, *d*, and an adhesive of any well known character 10 may be applied along the side edges of this flap, or flaps, or along the side edges of the plaited portion to more effectively secure these parts to each other and better secure the contained coins or pieces.

15 The sheet, *C*, may have its flap-portion, *c*, made with tapering side edges and this flap serves as a means for suspending the envelop in its open condition from a wall or other support with the coins, tokens or coupons in the several pockets exposed, it being assumed for this purpose that coins, when such are used, will be placed regularly or daily or otherwise in one or more of the pockets until the total number of 20 pockets shall be filled with coins, which practice has been used by me for special purposes as when it has been the desire that each pocket shall contain a coin of a given denomination and that the number of pockets 25 shall have a definite relation either to the amount the envelop shall contain or the number of days which shall be employed in filling the entire series of pockets with which the envelop is provided. The inner face of 30 the sheet, *C*, and the flap or extension thereof may be utilized for the display of printed matter indicative of the special object for which an envelop of this type may be employed, when such is the case, and such other 35 information as will carry out such object. Also, the extension, *c*, may be utilized as a 40

final covering-flap for securing the envelop in a folded condition and to this end said extension may be provided with an adhesive substance or other fastening means. The 45 outer face of the sheet, *C*, will correspond with the outer face of the usual envelop and upon this portion the name and address of a party may be written or printed when the package is to be transmitted through the 50 mails.

If desired, several plaited holders, *B*, may be flexibly connected say by the lines of stitching, *D*, or otherwise as shown in Fig. 4, without departing from the spirit of my 55 invention.

A device of the character described will be found quite desirable for the collection and safe transmission of coins and other insertible pieces and it may be made sufficiently 60 ornamental to serve as an object of attraction on walls or any other places.

Having thus described my invention what I claim as new and desire to secure by Letters Patent is:—

65 A coin, token, or coupon envelop, wrapper or holder composed of a single thickness of fabric having a portion folded on parallel lines to form plaits open at the top and closed at the bottom, said plaits forming 70 pockets for the reception of coins or other pieces, transversely extending spaced lines of stitching subdividing the plaited portion into separated rows of pockets, said sheet of fabric having an unplaited portion, and a 75 sheet fixed thereto and of sufficient area to fold over and cover the plaited portion, said unplaited portion having a flap foldable over the back of the folded portion.

80 In testimony whereof I affix my signature.

BESSIE ROBERTA CALLOW.
